(57) **CLAIM**

The ornamental design for a splatter shield, as shown and described.

DESCRIPTION

FIG. 1 is a top plan view of the new design of a splatter shield;

FIG. 2 is a bottom view thereof;

FIG. 3 is a front side view, the rear, left, and right being a mirror image thereof;

FIG. 4 is a front side view with a handle of the design raised, the rear view being a mirror image thereof;

FIG. 5 is a close up view of the center portion of the design thereof; and,

FIG. 6 is a close up view of the center portion of the design with the handle raised thereof.

The broken lines in all views are for illustrative purposes only and form no part of the claimed design.

1 Claim, 4 Drawing Sheets(56)
